UNITED STATES PATENT OFFICE.

CLIFFORD ORLO STEMEN, OF DETROIT, MICHIGAN.

ENVELOPE.

Application filed May 13, 1921. Serial No. 469,211.

To all whom it may concern:

Be it known that I, CLIFFORD ORLO STEMEN, a citizen of the United States, and a resident of Detroit, in the county of Wayne 5 and State of Michigan, have invented certain new and useful Improvements in Envelopes, of which the following is a specification.

This invention relates to envelopes and 10 more particularly to one of that type adapted for use where a reply is anticipated or for commercial use where an envelope is placed inside of another envelope for a reply, the present device serving to obviate 15 the necessity of employing or having on hand two different sizes of envelopes and permitting one to take the place of the two, thus resulting in a great saving in paper in addition to the cost of envelopes since envelopes 20 constructed in accordance with the present invention requires less paper than two ordinary envelopes and can be purchased considerably cheaper, while it may also be used for advertising purposes, mail matter 25 being placed inside and both flaps folded and mailed for one-cent postage. Furthermore, there will be no mistakes in the return address as it is always plain on the envelope or printed thereon by the party 30 or firm using the same.

The invention also contemplates the provision of an envelope embodying a novel arrangement of body and flap portions adapted to be folded in a novel way to constitute 35 sending and return envelopes, the parts being so arranged that all of the flaps which are provided with mucilage or other adhesive material are disposed on one side and the parts to be printed on the other side, 40 this constituting an important factor in the manufacture inasmuch as it saves two operations over the old time envelope where part of the mucilaged surface was on one side and part on the other, and the same with 45 the printing.

Other and further objects of my invention will become readily apparent to persons skilled in the art, from a consideration of the following description when taken in connection 50 with the accompanying drawings, wherein:

Figure 1 is a perspective view of the improved envelope folded when used as an original sending envelope.

55 Figure 2 is a plan view of the blank forming the envelope, and

Figure 3 is a vertical sectional view of the envelope when in initial folded position.

Referring to the drawings in detail in 60 which like reference characters designate corresponding parts throughout the several views, my improved envelope comprises a front portion 10 contiguous with the bottom edge of the back portion 11, both being of 65 equal size and formed of paper or other suitable material common in the art. At one end of the back portion 11 is provided an auxiliary front portion 12 corresponding in size to the front and back portions 10 and 70 11. The back portion 11 is preferably cut out or recessed in concaved formation, as indicated at 13 and a perforated or scored line 14 is provided between the front and back portions 10 and 11 in order that the 75 front portion 10 may be severed or detached along said line for a purpose to be herein-after explained. The front portion 10 is further provided with a flap 15 provided with an adhesive or mucilaged surface 16 along 80 the tapered edge portion thereof, said flap being designed to be folded on the line 17 and having in addition, spaced from said line and parallel thereto or sloping from the center to said line at the ends of the 85 front portion 10 a scored line 18 intermediately of which is disposed a small and preferably circular hole or aperture 19 adapted for the insertion of a pencil or the like or an envelope opener, in order that the flap 90 15 may be severed along said dotted, scored or perforated line 18 to permit opening of the envelope, after the same has been folded and forwarded as will be later described.

The auxiliary front portion 12 is provided 95 at the top edge contiguous with the edge of the back portion 11 having the recess 13 with a sealing or closing flap 20, the mucilaged or adhesive surface 21 of which is disposed at the same side as the mucilaged 100 surface 16 of the sealing or closing flap 15. It will also be observed that the flap 20 extends in the opposite direction from the direction of extent of the flap 15 when the blank is opened out, in the manner shown in 105 Figure 2 of the drawings. At the opposite or bottom end of the auxiliary front portion 12 is provided a narrow projecting flap 22 having a mucilaged or adhesive surface 23 on the same side of the blank corresponding with the sides at which the coatings 16 and 21 of the tapered sealing or closing flaps 110

15 and 20 are located, providing the flap 22 is first folded onto the front portion 12, the ends of said flap being free and being severed or slit as at 24 to permit this operation.

5 That is, the flap 22 is first folded onto the auxiliary front portion 12 and then coated simultaneously with the coating of the flaps 15 and 20.

At the free end of the auxiliary front portion 10 is disposed a narrow flap 25 having an adhesive coating 26 along the edge thereof and at the side with respect to which the flaps 5, 20 and 22 are coated, thus rendering it possible to simultaneously coat 15 these flaps with a single operation, thereby obviating two operations, as is usual. The front flap 10 and the auxiliary flap 12 are printed when the blank is opened out, but on the side opposite that which is provided 20 with the adhesive coating, the front portion 10 being provided in one corner with the name of the sender, as indicated at 30 and with the name of the addressee, as indicated at 29. On the auxiliary front portion 12 of 25 the body of the envelope, the name of the sender indicated at 27 is placed as the addressee as indicated at 29 and the name of the addressee indicated at 28 is placed in one corner as indicated at 30, thus constituting 30 a sending and return envelope in one section of paper or other material constituting the blank forming the device and obviating the necessity of employing a large and small or return envelope, requiring separate printing, 35 as with ordinary envelopes of this class or where two envelopes of different sizes are used, in addition to making it possible to provide the mucilage coating and the printing in two operations, instead of four operations in all, thus saving two operations and 40 materially reducing the cost as compared with other envelopes of this type or with the system of employing separate envelopes, one of which is disposed within the other as 45 a return envelope.

In the manufacture of the envelopes in accordance with the invention, using the blank described and shown in Figure 2 of the drawing, the auxiliary front portion 12 of 50 the body is folded at its edge contiguous with the edge of the back portion 11 indicated by the folding or scored lines 31, onto or against said back portion, the flap 22 having been first folded upwardly or against the inner 55 face of the front portion 12 and coated as heretofore described. This coating is moistened and pasted against the back portion 11 at the inside of the latter and then the flap 25 is folded around the edge 32 remote 60 therefrom and pasted or fastened in the outer face of the back portion 11, after which the flap 20 is turned into the envelope between the back portion 11 and the auxiliary front portion 12 without sealing the same. The 65 letter or mail matter is then placed in the

envelope and the portion 10 folded on the scored or perforated line 14 against the front face of the auxiliary front portion 12 so as to cover the return printed matter thereon of the sender and addressee after which the 70 flap 15 is subsequently bent on the scored or folding line 17 and sealed in the outer face of the back portion 11 in which condition the envelope is transported. The addressee on receiving the letter inserts an envelope opener or pencil in the hole 19 and opens the same along the perforated or scored line 18, the flap 15 remaining pasted to the back or being removed if desired, and found to be loose, or capable of being removed without fear of tearing the envelope. The contents will then be accessible and by detaching the front portion 10 along the perforated or scored line 14 adjacent to the line of fold of the front portion 10, the flap 20 75 having been withdrawn from between the back portion 11 and the auxiliary front portion 12, the envelope may be used with the addresses reversed as a return envelope. In practice, the flap 20 is made longer or larger 80 than the flap 15 so as to entirely cover and project beyond the tapered edge of the latter against the outer face of the back portion 11, in the event that the back 15 is left thereon or beyond the adhesive used to seal the 85 same, thereby avoiding an unsightly appearance and entirely covering the flap at the back so that the fact that the envelope has been used over may not be discerned although this latter feature is of secondary 90 importance. By reason of the perforated or scored line 18 being spaced from the folding line 17, the flap 15 will be severed below the top edge of the back portion 11 provided 95 with the cut out 13, thereby permitting the flap 20 to fold properly and neatly over the flap 15 and against the back 11 where it is secured when the envelope is sealed for return use. Also, by having the perforated or 100 scored line 18 spaced from the folding line 105 110 115 120 125 130 135 140 145 150 155 160 165 170 175 180 185 190 195 198 200 205 210 215 220 225 230 235 240 in connection with the scored or perforated line, greatly facilitates opening of the envelope by inserting a lead pencil or other implement and lessening the danger of damaging the envelope, this fact being important in view of its construction for return use. It will thus appear that the objects and advantages of the device heretofore specified, in an envelope intended for return use or where 10 replies are anticipated, have been fulfilled with obvious advantages over other devices of this character or the use of a return envelope generally used and requiring the necessity of having two sizes of envelopes. In 15 addition, the flaps 15 and 20 may be simultaneously folded into the envelopes and the envelope then mailed for one cent postage, both flaps arranged in this manner serving to stiffen the envelope so that accidental 20 opening or displacement is avoided. In addition, there will also be no mistake in the return address as it is always plain on the envelope or printed thereon by the party or firm using the same.

25 In view of the foregoing, it is thought that

the operation of the device will be readily understood and in view of the simplicity and practical value, that it will readily commend itself to those skilled in the art.

Having thus particularly described and 30 ascertained the nature of the invention, what I claim is:—

An envelope having a front portion and a back portion and having a perforated line constituting the line of fold between said portions, an auxiliary front portion connected with the back portion and disposed between the front and back portion, said auxiliary front portion having a flap cooperable with the back portion, said front portion also 40 having a flap adapted to be affixed to the back portion and having a perforated line above the affixed part thereof and further having an opening located on said last mentioned perforated line and adapted to admit 45 of the insertion of an instrument for tearing the flap of said front portion on its perforated line.

CLIFFORD ORLO STEMEN.
